OIL WELL FORMATION TESTER

George H. Ramsey, Tulsa, Okla., assignor to
Standard Oil Development Company, a corpora-
tion of Delaware

Application February 1, 1950, Serial No. 141,635

6 Claims. (Cl. 166—1)

1

The present invention is concerned with an improved device for securing samples of formation fluids from a well bore. More specifically it is concerned with a formation tester wherein a shaped explosive charge is used to expose a fresh surface of the formation which is then immediately covered by a rubber disc packer, making it possible to secure a sample of the fluids from the freshly exposed formation without contamination by drilling mud or other fluid.

In conventional oil well drilling operations fluids known as drilling muds are employed to aid in carrying away cuttings and also to maintain a hydrostatic head in the well to prevent the uncontrolled escape of gases or liquids from various formations encountered during drilling. One disadvantage of drilling with a drilling mud is that the sampling of natural fluids occurring in various formations is thereby rendered difficult. To overcome this disadvantage various types of formation testers have been devised which are provided with means for reducing the hydrostatic pressure in the vicinity of the formation to be tested and for establishing communication between the formation and suitable conduits or chambers for collecting the fluid samples with but little or no contamination by drilling mud.

It is one object of this invention to provide an apparatus which will penetrate a desired area of a formation, seal off the area from contamination by drilling mud and establish communication between the sealed off area and a suitable sampling means. It is a more specific object of the invention to provide an apparatus which will penetrate a formation by the force of an explosive charge and which will immediately set an elastic seal over the freshly penetrated area, formation fluids then being drawn from the formation through appropriate conduit means in the elastic seal.

The invention will be more readily understood from the ensuing description and from the drawing in which:

Figs. 1 and 2 are sectional elevational views of the device with its parts set in proper position for lowering into a bore hole, Fig. 2 being a lower continuation of Fig. 1;

Fig. 3 is a view of the portion of the device shown in Fig. 2, in position in the bore hole with its parts set against the walls of the bore hole prior to detonation of the explosive charge;

Figs. 4 and 5 are sectional elevation views of the device with the parts in position for raising the device out of the bore hole after completion

of the test, Fig. 5 being a lower continuation of Fig. 4; and,

Fig. 6 is a schematic design of a suitable electrical circuit and associated elements for actuating the recoil-piston-releasing solenoid of the device and for firing the explosive charge.

Referring now specifically to Figures 1 and 2, it will be seen that this device is supported on a sub 2 which is adapted to be attached to the end of a drill pipe 1. Fastened to the lower end of sub 2 is a cam sleeve 3 provided with cam faces 13 and 13a and with inner annular bearing shoulder 5. Rotatably seated within sleeve 3 and supported by shoulder 5 is a supporting sleeve 6 to the lower end of which is attached an elongated mandrel 7 terminating at its lower end in a protective nose plug 8.

Slidably fitted into the lower end of mandrel 7 and at right angles thereto is a recoil cylinder 9 into which is fitted recoil piston 10. Piston 10 is adapted to slide within the cylinder 9 and its arm extends out of cylinder 9 through an end piece 24 which holds packing material 14 against the arm of piston 10 to give a fluid-tight seal.

A pair of spring positioners 12 are pivotally attached to supporting sleeve 6 and rest against cam face 13. Attached to each of the spring positioners is an elongated flat spring member 11. One of the springs 11 is pivotally attached at its lower end to shoulder 38 on the end of the arm of piston 10. The other spring 11 is pivotally attached at its lower end to an outer portion of slidable cylinder 9. With the spring positioners 12 in the position shown in Fig. 1 the springs 11 exert a bias on cylinder 9 and on piston 10 tending to urge each of the members outwardly from mandrel 7. Opposing this outward bias are a pair of releasing arms 15 and 16, the upper hooked end of arm 15 engaging notch 17 in cylinder 9, and the notch 18 at the end of arm 16 engaging shoulder 38 of piston 10. The inner arms of 15 and 16 communicate with an armature 21 by means of linking arms 20 and 22 so that, as armature 21 moves upwardly by the action of solenoid 23, arms 15 and 16 will turn on pivot points 19 and 19a and release cylinder 9 and piston 10.

The outer end of cylinder 9 is provided with a cone-shaped recess 26 surrounded by a more-or-less saucer-shaped flexible disc 25. Conveniently, disc 25 may be made of natural or synthetic rubber. Fitted within opening 26 is a cone-shaped lining of explosive material 27. A metal liner 28 may be inserted also, to cover the explosive charge. A frangible spacing and seal

ing cap 29 covers the opening 26 so as to leave an air space 30. The cap may conveniently be made of plastic material such as a molded phenol-aldehyde resin, cellulose acetate, or the like. Projections 29a on cap 29 are adapted to rest against the wall of the bore hole so as to give the proper standoff distance for the shaped explosive charge 27 for maximum effectiveness. These projections also keep the elastic packer disc 25 away from the walls of the borehole until after the explosive has been detonated, facilitating the blowing away of mud around the packer disc and also minimizing damage thereto by the explosion. Cone-shaped opening 26 terminates at its apex in a detonator chamber 31 into which is fitted a detonating cap 32. The latter is connected to an electrical lead 33 through which an electrical charge may be sent to set off the detonator. Wire 33 is connected to switch 35 whose function will be discussed later.

If desired the movable parts of the device may be protected against damage when the apparatus is being lowered into or raised out of the bore-hole by fastening to the apparatus a cylindrical jacket extending from sleeve 3 down to nose plug 8, the jacket being provided with suitable openings for springs 11, piston shoulder 38, cylinder 9 and disc 25. In the interest of clarity this jacket is not shown in the drawing, but its construction is a simple matter.

It will be seen from the foregoing description that the device of this invention may be lowered into a bore hole, after which the tripping mechanism associated with solenoid 23 may be actuated so as to set the disc shaped packer 25 adjacent the wall of the bore hole. This may be done by lowering through the drill pipe an overshot which will come into contact with overshot plug 4 in the interior of sub 2 and make electrical contact with contact wire 62. As described more fully in connection with Fig. 6, contact wire 62 is connected electrically through switch 35 to solenoid 23. After electrical contact has been established with plug 4 an electrical current is sent down through the cable on which the overshot is supported and armature 21 is actuated to release cylinder 9 and piston 10. The position of the various parts after this has been done is shown in Fig. 3. It will be seen that sealing cap 29 now rests against the wall of the bore hole 101 and that projection 48 on the end of piston 10 engages the bore hole wall on the opposite side. Projecting ear 37 on cylinder 9 has moved outwardly from switch 35 and thus permitted plunger 36 to move outwardly. As discussed later in connection with Fig. 6 this movement of plunger 36 actuates switch 35 so that electrical contact is made between plug contact wire 62 and firing wire 33. Thus the sending of an additional electrical impulse down the cable will set off detonating cap 32 which in turn will fire shaped charge 27. The jet formed by the shaped charge will penetrate the formation to a depth determined by the amount of explosive contained in the shaped charge. Thus, as depicted in Fig. 5, a hole 103 will be blown out of the stratum 102 from which the desired test is to be made. The explosion will also break the plastic sealing cap 29 and permit packer 25 to set up against the wall of the bore hole. At the same time the explosion will drive drilling mud from between the wall of the bore hole and packer 25 so that the latter will seat readily on the edges as an immediate after-effect of the explosion and will be held against the bore hole wall by mud pressure.

In order to cushion the recoil from the explosion, cylinder 9 is preferably filled with oil. The head of piston 10 is provided with a small opening 41 which serves as a pressure equalizing port and allows fluid flow from either side of the piston head so that when the piston and cylinder are first released by the solenoid-actuated release mechanism the piston and cylinder will move outwardly by virtue of the bias exerted by springs 11 until projection 48 and sealing cap 29 engage the walls of the bore hole as already described. Under a shock loading, however, immediately after the explosion, the piston and cylinder will move only slightly because of the oil cushion. It is convenient to provide a volume-expanding chamber 43 communicating with the interior of cylinder 9 through flexible oil resistant conduit 42 in order to provide for expansion and contraction of oil volume resulting from changes in piston rod displacement during movement.

It will be seen that after the explosive has been detonated, opening 26 will be in direct communication with production passage 45 which connects with production control valve 50 through a flexible production tube 46. Thus after packer 25 has been set against the formation, fluids present in the formation will be permitted to flow through tube 46, valve 50 and conduit 55 into the interior of sub 2 and the empty drill pipe 1. When it is desired to complete the test and stop the flow of formation fluids, valve 50 may be turned so as to shut off communication between tube 46 and conduit 55 and to establish communication between tube 46 and pressure-equalizing port 56 so that drilling mud will flow through tube 46 into the explosion hole, equalizing mud pressure on both sides of packer 25 to facilitate unseating it from the bore hole wall. In order that valve 50 may be turned when desired, an L-shaped arm 51 is provided, the lower end of which fits into cavity 52 in mandrel 7. Since sub 2 is adapted to turn relative to mandrel 7 and supporting sleeve 6, it is apparent that rotation of drill pipe 1 while piston 10 and cylinder 9 engage the walls of the bore hole will cause valve 50 to turn. At the same time cam sleeve 3 will turn relative to sleeve 6, presenting cam faces 13a which will move spring positioners 12 on their pivots and thus urge springs 11 and 12 inwardly as shown in Figure 4. This in turn will slide piston 10 and cylinder 9 inwardly as shown in Fig. 5.

Cam faces 13a are placed 90° from cam faces 13 about the circumference of sleeve 3 and valve 50 is designed to establish communication between tube 46 and either port 56 or conduit 55 for every 90° rotation of valve part 50a relative to valve part 50b. Thus rotation of sub 2 relative to mandrel 6 through 90° will actuate valve 50 and spring positioners 12.

A schematic diagram of an electrical circuit and associated elements for actuating solenoid 23 and for detonating the explosive charge is shown in Fig. 6. Overshot 59 lowered on single conductor cable 60 engages overshot plug 4 so that the electrical contact is made between the conductor in cable 60 and contact 62 through contact springs 61. Lead wire 63 connects plug contact 62 to one side of contact points 64 and 64a at switch 35. When plunger 36 is held in against the pressure of spring 65 by projection 37 electrical contact is established between lead 63 and lead 67 so that an electrical impulse sent down through cable 60 will be sent through coil 68 in solenoid 23 and will thus raise armature 21. Movement of projection 37 away from switch 35 as a result of releasing cylinder 9 by the solenoid

action as previously described will permit spring 65 to move contact element 66 to contact points 64a so that electrical contact will then be established between lead 63 and lead 33. When an additional electrical impulse is now sent down through cable 60, current will be conducted to detonating cap 32. In each case the return side of the circuit is established through the supporting structure and the drill pipe as a ground. It will be readily apparent that the need for switch 35 can be avoided by employing multiple conductor cable rather than single conductor cable and using separate circuits for actuating solenoid 23 and for setting off detonating cap 32.

It is not intended that this invention be limited by the specific embodiments thereof described in the foregoing specification, for it is evident that many modifications thereof can be made by persons skilled in the art without departing from the spirit and scope of the invention as defined by the following claims.

What is claimed is:

1. Improved device for testing for the presence of fluids in a formation transversed by a borehole, comprising a body adapted to be lowered into the borehole and provided with a hollow portion adapted to receive a sample of fluid, a cylinder slidably supported in a horizontal position by said body, said cylinder having an open end, a closed end, and a recess on the exterior of the closed end, a piston slidably fitted within the open end of said cylinder, a shaped explosive charge placed within said recess, a frangible cap covering said recess, a flexible disc attached to the closed end of said cylinder and provided with a central opening communicating with said recess, spring means urging said piston and said cylinder outwardly from said body toward the walls of the borehole, releasable latching means normally opposing said outward movement of said piston and said cylinder, and conduit means connecting said recess with said hollow portion of said body.

2. Improved device for testing for the presence of fluids in a formation traversed by a borehole, comprising a body attachable to the lower portion of a drill pipe and provided with a central hollow portion communicating with the interior of said drill pipe, an elongated mandrel rotatably supported below said body, a cylinder slidably fitted in a horizontal position in said mandrel, said cylinder having an open end and a closed end, and being provided with a cone-shaped recess on the exterior of the closed end, a piston slidably fitted within the open end of said cylinder, a shaped explosive charge fitted within said exterior recess in said cylinder, a frangible cap covering said recess, a flexible disc having an opening in its center and attached at said central opening to the closed end of said cylinder with its central opening adjacent said recess, a plurality of flat spring members one of which is attached at its lower end to the closed end of said cylinder and another of which is attached at its lower

end to the outer end of said piston, said springs being pivotally attached at their upper ends to said mandrel, means adapted to turn said springs on their pivots to a first position in which said springs urge said piston and said cylinder outwardly from said body toward the walls of the borehole and to a second position in which said springs urge said piston and said cylinder inwardly away from said walls, releasable latching means normally opposing said outward movement of said cylinder and said piston, and flexible conduit means connecting said recess with said central hollow portion of said body.

3. Device as defined by claim 2 including an oil-tight seal fitted in the open end of said cylinder about the body of said piston and an expandable oil chamber communicating with the interior of said cylinder, said piston being provided with a head having a pressure equalizing port.

4. Device as defined by claim 2 in which said means adapted to turn said springs comprises a sleeve depending from said body and surrounding the upper portion of said mandrel, said sleeve being provided with two pairs of diametrically opposed cam faces engageable with the upper portions of said springs and spaced circumferentially 90° apart, one pair of cam faces being pitched to turn said springs in a direction urging outward movement of said piston and said cylinder and the other pair of cam faces being pitched to turn said springs in a direction urging said inward movement of said piston and cylinder.

5. Device as defined by claim 2 including a solenoid-actuated armature for operating said releasable latching means, and electrical circuit means for furnishing current to said solenoid and to a detonator for said explosive charge.

6. Device defined by claim 2 including a two-way valve in the line of flow between said flexible conduit means and said central hollow portion of said body and means adapted to turn said valve from a first position to a second position upon rotation of said body relative to said mandrel by a predetermined amount, said valve being provided with a port adapted to contact fluid in the bore hole exterior of the device, said valve establishing in said first position a path of fluid communication between said flexible conduit and said central hollow portion of the body and in said second position blocking said last-named path of communication and establishing fluid communication between said port and said flexible conduit.

GEORGE H. RAMSEY.
